(57) **CLAIM**

The ornamental design for radio frequency processing equipment as shown and described.

DESCRIPTION

FIG. 1 is a perspective view of the radio frequency processing equipment of the claimed design showing the right and front sides.

FIG. 2 is a perspective view of the radio frequency processing equipment of FIG. 1 showing the left and back sides.

FIG. 3 is a front view of the radio frequency processing equipment of FIG. 1.

FIG. 4 is a rear view of the radio frequency processing equipment of FIG. 1.

FIG. 5 is a right side view of the radio frequency processing equipment of FIG. 1.

FIG. 6 is a left side view of the radio frequency processing equipment of FIG. 1.

FIG. 7 is a top view of the radio frequency processing equipment of FIG. 1; and,

FIG. 8 is a bottom view of the radio frequency processing equipment of FIG. 1.

The dash-dash broken lines in the drawings illustrate portions of the radio frequency processing equipment that form no part of the claimed design.

The surface line shading is included for clarification purposes.
